US0D1056184S

(12) **United States Design Patent** (10) **Patent No.:** **US D1,056,184 S**
(45) **Date of Patent:** **** Dec. 31, 2024**

(54) **PET WATER DISPENSER FILTER**

(71) Applicant: **Zhifeng Peng**, Shenzhen (CN)

(72) Inventor: **Zhifeng Peng**, Shenzhen (CN)

(**) Term: **15 Years**

(21) Appl. No.: **29/939,498**

(22) Filed: **Apr. 26, 2024**

(51) **LOC (14) Cl.** **23-01**

(52) **U.S. Cl.**

USPC **D23/209**

(58) **Field of Classification Search**
